UNITED STATES PATENT OFFICE.

CHARLES J. DORSEY, OF BALTIMORE, MARYLAND, ASSIGNOR, BY DIRECT AND MESNE ASSIGNMENTS, TO ACME FUSE BOX COMPANY.

PLURAL-FUSE CUT-OUT.

SPECIFICATION forming part of Letters Patent No. 697,935, dated April 15, 1902.

Application filed November 26, 1900. Renewed September 5, 1901. Serial No. 74,389. (No model.)

To all whom it may concern:

Be it known that I, CHARLES J. DORSEY, a resident of Baltimore, in the State of Maryland, have invented certain new and useful 5 Improvements in Plural-Fuse Cut-Outs; and I do hereby declare the following to be a full, clear, and exact description of the invention, such as will enable others skilled in the art to which it pertains to make and use the same. 10 The invention relates to plural-fuse cut-outs and cut-out boxes for electric circuits, and has for its objects to simplify prior constructions and increase their efficiency.

The invention consists in the construction 15 herein described and pointed out.

In the accompanying drawings, Figure 1 is a perspective view of the plural-fuse cut-out when open. Fig. 2 is a central section of the same device closed. Fig. 3 is a front view of 20 the cut-out when closed, and Fig. 4 is a partial elevation of a switch device.

Numerical 1 denotes a frame of any convenient or desirable form and material to contain metal electric connections and insulating material *x*. Preferably the frame is provided with brackets 2 for securing it to a car or other structure.

3 denotes a frame to hold a cover 4, and 5 represents hinges connecting the frames. If 30 desired, the frame 3 may have a casing-plate 6.

7 denotes ventilating-apertures in the cover and its casing-plate. The form and number of these openings are not material and may be varied at pleasure, or they may be dispensed 35 with, without defeating the other parts of the invention.

9 and 10 denote wires of an electric circuit secured, respectively, to a conducting-bar 11 and a conducting-disk 12 by screws or equivalents 40 13.

15 denotes fusible conductors connecting the bar and a series of bent and straight conducting-blocks, (denoted by 17.)

To the disk 12 is fixed a ratchet-disk 14, 45 coacting with a similar disk 18, fixed to non-conducting material *x*. The ratchet has a sleeve rotating in a central opening in the fixed disk 18, as indicated in Fig. 2. It is

not essential that the disks 12 and 14 be separate parts.

16 denotes a key having a non-conducting handle and a stop or shoulder provided with an index-finger to point to marks or figures I, II, III, IV, and V, corresponding in situation to blocks 17 within the cover or case. The 55 key has a part angular in cross-section, as indicated in Figs. 2 and 4, and this part suitably fits a similarly-shaped opening in the disk and in the ratchet 14. The key is pivoted to turn in the case and operates to rotate the disk and ratchet 14. The key is retained in operative situation by a pin 20, situated within the case or in a recess 21 in its wall.

An electric circuit is established between 65 the disk 12 and bar 11 by a spring 22, which may conveniently be made approximately in the form of the letter S, as indicated, though the particular form is unessential.

By manipulating the key this spring can be 70 used to electrically connect the disk with each of the several blocks 17 and with their respectively connected fuses 15. The ratchet-disk holds the conducting-disk 12 under each of its adjustments. In practice the disk, 75 pointer, and spring will be initially set as indicated in the drawings, and in case of the burning out of a fuse they will be suitably turned to establish connections through the next succeeding block 17. Several of these 80 blocks are bent and arranged in connection with one straight block, as shown. The precise number of blocks is not material; but it is desirable to group their ends about the circuit-making disk, substantially as represented, in order to reduce the size of the device as a whole and to provide for the use of a single key and spring and avoid the necessity of removing the key in a structure using such spring as a contact-maker.

The fuses 15 may be of any suitable form and material and are made replaceable by means of securing-screws or binding-posts.

23 denotes channels or receptacles for the fuses. Preferably these and the blocks 17 and 95 bar 11 will be formed or fixed, as the case may

be, in the body of non-conducting material by molding said material in a plastic state and subsequently hardening it. The part of the cover having receptacles 23, which coact to inclose the fuses, can also be formed by molding and ventilating openings of any suitable shape provided therein, if desired.

While it is practicable to make the box of two parts molded from a non-conducting material or composition, other forms built up of separate pieces are not excluded. The frames that surround the non-conducting material are convenient and suitable, but not essential in all cases, and the two parts of the box or inclosure may be connected in any practicable manner and the non-conducting portions may be made partly or wholly of wood without departing from the invention.

20 A special guard to prevent fused metal being carried toward the disk 12 and welding the parts together is produced by a suitable groove or depression 25, formed in the blocks and in the intermediate non-conducting material. This groove is made to receive a rib 24, formed on the body of non-conducting material in the cover, which rib being situated in the plane of the fuse obstructs the transportation of metal and prevents the welding of a block and spring. Obviously the form and dimensions of the groove and rib may be varied, and it is further obvious that the means herein set forth for obviating the objectionable effects of excessive electrical currents are adapted to provide that fuse-boxes of comparatively small size and weight may be used with safety.

Having thus described my invention, what I claim as new, and desire to secure by Letters 40 Patent, is—

1. In a plural-fuse cut-out, a series of parallel insulated fuses, a series of insulated conducting-blocks each adapted to be put in an electric circuit with a fuse, and a rotatable circuit-closing device having a path tangential to each block, said blocks being of unequal lengths and comprising parts that are

curved to surround the circuit-closing device and present faces in the path of said device.

2. A series of fuses adapted to be successively put in an electric circuit, a fuse-box comprising parts separable near the plane of the fuses, a circuit-closer adapted to be electrically connected with each fuse in turn, 55 said closer comprising a movable ratchet and a corresponding fixed ratchet, the latter being fixed in one part of the box and the other carried by the other part of the same.

3. A series of fuses adapted to be successively put in an electric circuit, a fuse-box comprising parts separable near the plane of the fuses, a circuit-closer adapted to be electrically connected with each fuse in turn, 60 said closer comprising a movable ratchet and a corresponding fixed ratchet, the latter being fixed in one part of the box and the other carried by the other part of the same, a ratchet-operating key, and a spring pressing the ratchets together, said spring and key being 65 carried with the same separable part of the box that carries the movable ratchet.

4. A series of fuses adapted to be successively put in an electric circuit, a fuse-box comprising parts separable near the plane of the fuses, a circuit-closer adapted to be electrically connected with each fuse in turn, 75 a series of conducting-blocks in the path of the circuit-closer, each of said blocks being provided with a groove, means for connecting a fuse to each block, and non-conducting ribs adapted to enter the grooves, the blocks being situated in one part of the box and the ribs in the other, and the ribs extended transversely through a plane passing between the 80 parts.

In testimony whereof I have signed this specification in the presence of two subscribing witnesses.

CHARLES J. DORSEY.
